UNITED STATES PATENT OFFICE.

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA.

TROLLEY-CONDUCTOR DEVICE.

1,370,050.

Specification of Letters Patent.

Patented Mar. 1, 1921.

Application filed March 9, 1918. Serial No. 221,390.

To all whom it may concern:

Be it known that I, WILLIAM SCHAAKE, a citizen of the United States, and a resident of Pittsburgh, in the county of Allegheny and State of Pennsylvania, have invented a new and useful Improvement in Trolley-Conductor Devices, of which the following is a specification.

My invention relates to trolley-conductor devices and particularly to frogs, crossings and similar structures.

One object of my invention is to provide a device of the above-indicated character that shall be simple and durable in construction and economical to manufacture.

Another object of my invention is to provide, in a trolley device having a body portion and separable approach members, a single readily-interchangeable insert member that is adapted to be placed between the body portion and the approach members to increase the length of the device and to prevent coöperating current-collecting devices, such as trolley wheels, from becoming wedged between the conductors near the same.

Figure 1 is a partial top plan view of a trolley frog embodying my invention, and Fig. 2 is a side view of the device shown in Fig. 1.

A trolley frog 1, of a usual type, only one end of which is shown, comprises, in general, a body member 2 having channel portions 3 for receiving converging conductors 4 that are attached thereto in any suitable manner, eye members 5 for attachment to guy-wires or other supports (not shown) and a buffer portion 6. Ordinarily, the portion 6 is provided to receive the shock that is imparted to the frog when a trolley wheel or pole, that is approaching the frog, becomes disengaged from its conductor and rises between it and the adjacent conductor.

Renewable conductor-embracing wearing or approach members 7 may be attached directly to the body member 2 by bolts 8 and nuts 9. With such devices, the jumping of a trolley wheel may occur, and the wheel, the harp or the pole may become wedged so tightly between the conductors of a frog that removal thereof may be effected only with great difficulty.

In order to prevent the trolley wheel from becoming wedged between the conductors, I

provide a simple, economical and readily-applicable insert or extension member 10 that may be adapted for coöperation with any particular type of frog or crossing having the above-mentioned general character without any alteration whatever in the frog or crossing.

As shown, the member 10 comprises conductor-embracing channel portions 11, similar to the channel portions 3 of the frog 1 which constitute continuations of the same, a transverse web connecting portion 12 between the channel portions 11, and a buffer portion 13 similar to, and for the same purpose as, the portion 6. The member 10 is attached to the frog 1 by the bolts 8 and plates 14, which may or may not be integral with the member 10, similar to the manner in which the approach members 7 are ordinarily attached thereto. Likewise, the members 7 are attached to the outer ends of the member 10 in a manner similar to that in which they are ordinarily adapted to be attached to the frog.

Since the angle between conductors at a frog is very small, usually about eight degrees, I provide, by my invention, a closure for the same at a sufficient extent away from the frog to entirely preclude the possibility of a trolley wheel or other current-collecting device from becoming wedged therein.

Furthermore, the general character of the frog is maintained, being simply lengthened, and the contact-bearing surface for engagement with a current-collecting device is disposed only along the path of the conductors, as in the usual frog.

While I have shown and described a particular form of my invention, it will be obvious to those skilled in the art that many changes may be effected therein without departing from the spirit and scope thereof, as indicated in the appended claims.

I claim as my invention:

1. The combination with a trolley-frog provided with a portion normally adapted to receive a renewable conductor-engaging approach member, of an insert member adapted to engage said trolley-frog in the place of the approach member, and means for securing the approach member to the insert member.

2. The combination with a trolley-frog having diverging conductor-engaging arms

provided with means for supporting renewable approach members, of an insert member adapted to be held at one end in engagement with said trolley-frog by said supporting means, and similar means at the other end of the insert member for supporting the approach members, the said insert member comprising means for preventing a current-collecting device from becoming 10 wedged between the conductors.

3. The combination with a trolley-frog comprising a body member and a conductor-engaging approach member, of means for increasing the length of said trolley-frog 15 comprising an insert member adapted to be placed between said members in coöperative relation thereto.

4. The combination with a trolley-frog comprising a body member and a conductor-engaging approach member, of means for increasing the length of said trolley-frog comprising an insert member adapted to be placed between said members in coöperative relation thereto, said insert member 20 having a laterally extending portion for

preventing a current-collecting device from passing upwardly beyond the same.

5. The combination with a trolley frog adapted to fill the angle between converging conductors for a definite distance from the apex of the same, of means for preventing wedging of a current-collecting device between said conductors, said means comprising a member to be added to said trolley-frog to permit the latter to guide said device along the frog over its usual path in alinement with the conductor.

6. A device for preventing wedging of a trolley contactor between the converging arms of a trolley frog comprising a member 40 adapted to fill the space between the converging conductors for a relatively great distance from the frog and having integral conductor-embracing channel portions for engagement with a current-collecting device.

In testimony whereof I have hereunto subscribed my name this 28th day of Feb., 1918.

WILLIAM SCHAAKE
